(57) **CLAIM**

The ornamental design for a building, as shown and described.

DESCRIPTION

FIG. 1 is a front perspective view of an embodiment of a building showing my new design;

FIG. 2 is a front elevational view thereof; and,

FIG. 3 is a back perspective view of another embodiment of a building showing my new design, it being understood that the front perspective view and the front elevational view of this embodiment are the same as the previous embodiment.

1 Claim, 3 Drawing Sheets

FIG. 1

FIG. 2

FIG. 3
